UNITED STATES PATENT OFFICE.

WILLIAM SCHWIER, OF SEATTLE, WASHINGTON.

MONORAIL FROG.

Application filed July 18, 1923. Serial No. 652,385.

To all whom it may concern:

Be it known that WILLIAM SCHWIER, a citizen of the United States, residing at Seattle, in the county of King and State of Washington, has invented new and useful Improvements in Monorail Frogs, of which the following is a specification.

In a monorail frog, the invention has for its purpose to provide a fulcrumed monorail and simple and improved means operatively connecting with the opposite ends of the monorail, in conjunction with means connecting with the switch points to insure simultaneous operation of the monorail and the switch points.

Another purpose is to provide a device of this kind embodying improvements over the construction of monorail frog set forth, illustrated and claimed in the patent to William Schwier, issued April 3, 1923, Patent No. 1,450,758, and like in this patent, the present invention aims to provide a continuous rail tread surface in passing into and out of a siding to avoid the gap or interval ordinarily required to provide a passage for the wheel flange.

Still another purpose is to provide a monorail frog with means to lock it in alining register either with the main rail or the siding rail.

A further purpose is to provide means for automatically releasing the lock member prior to moving the monorail frog in order to permit the frog to be moved in alining register with either the main rail or the siding rail.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a perspective view of a section of track showing the main rails and siding rails, the switch points and the monorail frog constructed in accordance with the invention.

Figure 2 is a plan view showing one of the

main rails and one of the siding rails with the frog rail in alining register with the main rails.

Figure 3 is a plan view similar to Figure 2, showing the frog rail in alining register with the sections of the siding rail.

Figure 4 is a sectional view on line 4—4 of Figure 2.

Figure 5 is a plan view of one end of the base or bed plate which operatively supports the frog rail.

Figure 6 is a perspective view of one of the frog rail shifting rods.

Figure 7 discloses views of the frog rail supporting chair and a lock member which fulcrums on one side of the chair.

Figure 8 is a sectional view on line 8—8 of Figure 3.

Referring to the drawings, 1 designates conventional ties which operatively support the main rails 2 and 3 and the siding rails 4 and 5. Mounted on certain of the ties is a bed or base plate 6 which may be constructed of any suitable metal, either heavy plate metal or rolled metal, preferably the latter. The bed or base plate has openings or cut-away portions 7 to lighten the same. Furthermore, the bed or base plate is formed or shaped with depressions or arches 8 which straddle the ties and act to prevent not only movement of the base or bed plate but also creeping of the ties. In providing these arches or depressions 8, the base or bed plate is caused to be formed with countersinks 9 which assume intervening positions relative to the ties. In other words, the countersinks 9 engage between the ties as shown.

A chair 10 constructed for the support of the frog rail 11 is provided. This chair is of a shape in cross section to conform to and receive the web and base of the frog rail, there being a bolt 12 passing through the upstanding flanges of the chair and the web of the frog rail with a nut 13 to hold the chair to the frog rail. The under face of the chair has a downwardly protruding threaded stud 14 which passes through an opening 15 in the center of the base or bed plate for the purpose of fulcruming the chair and, since the frog rail is supported therein, said rail is fulcrumly mounted. A collar 16 is mounted upon the stud 14 and is interposed between the base or bed plate and the under surface of the chair so as to

prevent the entire under face of the chair from engagement with the base or bed plate. In this way, the friction is reduced to a minimum. A suitable washer 17 and a nut 18 are applied to the downwardly protruding stud to hold the same in position and to insure the fulcruming of the chair 10.

At opposite ends of the bed or base plate and protruding downwardly from the opposite sides thereof are guides 19 in which the frog rail operating bars or rods 20 are mounted. Each bar or rod has an elongated loop 21 and cam lugs 22. The opposite ends of the frog rail are supported in rail chairs 23 and 24. The rail chair 23 is located adjacent one end of the base or bed plate while the chair 24 is adjacent the opposite end. The chairs 23 and 24, like the chair 10, are shaped in cross section to conform to and receive the base and web of the frog rail. However, the upstanding flanges of the chairs 23 and 24 are not secured to the web of the frog rail, therefore, if necessary, the chairs 23 and 24 are permitted to have slight movements longitudinally of the frog rail in order to avoid any undue binding of the moving parts.

Projecting downwardly from the under surfaces of the chairs 23 and 24 are studs 25 on which sleeve rollers 26 are journaled. Plate washers 27 are also mounted upon the studs adjacent the opposite ends of the sleeve rollers, there being nuts 28 threaded on reduced extensions 29 of the studs. The sleeve rollers 26 assume positions in the elongated slots or loops 21 of the operating bars and when the bars 20 are reciprocated, one in one direction and the other in the opposite direction, certain of the ends of the slots 21 or loops 21 abut the sleeve rollers 26 and shift the frog rail. The lower plate washers 27 engage the under walls of the sides of the loops 21 while the upper plate washers 27 engage with the upper face of certain of the countersinks in the bed or base plate.

The sleeve rollers also engage through the arcuate slots 30 which are formed in certain of the countersinks of the base or bed plate. The slots 30 are concentric with the fulcrum of the frog rail. The cam lugs 22 of the operating reciprocating bars also protrude through the arcuate slots 30 and are designed for the purpose of actuating the pivoted locking devices 31. The locking devices comprise the bodies 32, certain of which engage with the upper surfaces of certain of the countersinks in the bed plate when the frog rail is in one position while the others engage with diagonally opposite portions of the upper surfaces of said countersinks when the frog rail is in a reverse position. In other words, diagonally opposite locks engage with the upper surfaces of certain of the countersinks when the frog rail is in alining register with the sections

of the main rail and when the frog rail is in alining register with the sections of the siding rail, the other diagonally opposite locks engage with the upper surfaces of the same countersinks.

Projecting from the bodies 32 of the locks are arms 33 which are fulcrumed upon bolts 34 which are mounted in ears 35 projecting from the remote faces of the upstanding flanges of the chairs 23 and 24. Abutment plates 36, 37, 38 and 39 are secured, as shown, to the upper surfaces of certain of the countersinks of the base or bed plate and alternately with certain of which the locks 31 engage to retain the frog rail in different positions. When the frog rail is in alining register with the sections of the main rail, as in Figure 2, certain diagonal locks 31 abut the abutment plates 36 and 39, retaining the frog rail in such position and preventing the rail from being returned in aligning register with the sections of the siding rail.

It will be noted that suitable bolts 40 are used for holding the adjacent siding rail sections and the main rail sections in positions in engagement with spacing plates 41 which are formed in the usual manner to conform to the contour of the webs and bases of the rails. By the bolts 40 and the spacing plates 41, the siding rail and main rail sections are held in relatively rigid positions. To further secure and hold such rail sections in place, rail retaining plates 42 are secured to the upper surface of the bed or base plate and are constructed to overlie the bases of such rail sections. These rail holding or retaining plates 42 are disposed in order to constitute abutments for the ends of the frog rail so that when the frog rail is held against fulcruming movement in the direction of the abutments 36 and 39, certain diagonal rail retaining or holding plates 42 will prevent movement of the frog rail in the opposite direction. The same thing is true of the other diagonal retaining and holding plates 42, that is, when the frog rail is in alining register with the sections of the siding rail as in Figure 3. When the frog rail is in the position shown in Figure 3, certain diagonal locks 31 engage the abutments 37 and 38, thereby preventing movement of the frog rail in the direction of such abutments, that is, until the abutments are raised or tilted upon their fulcrums.

In order that the frog rail may move, it is necessary to reciprocate the bars 20, one in one direction, the other in the opposite direction. These bars 20 have a slight movement to raise the locks without effecting any action upon the frog rail. In order to effect a raising action of the locks, the inclined edges or faces of certain diagonally opposite cam lugs 22 will ride or

cam upon the inclined or cam bottoms 43 of the notches formed on the under surfaces of the locks, as in Figure 4, and thereby raise certain diagonal locks out of engagement with the abutments 36 and 39. To effect this movement, the operating bars 20 are moved in the direction of the arrows *a* in Figure 2. To move the frog rail from the position shown in Figure 3 to that shown in Figure 2, it is necessary to move the bars 20 in the direction of the arrows *b* in Figure 3 which will raise the locks out of engagement with the abutments 37 and 38. Just when the locks are free of the abutments, whether the frog rail is moved in one direction or the other, or a very short time after freeing the locks of the abutments, one of the ends of the slot or loop 21 engages the sleeve roller 26, thereby imparting movement to the frog rail.

The operating bars or rods are in sections 44 and 45 united by the turn-buckles 46 for the purpose of lengthening or shortening the bars to permit the frog rail to be properly positioned so that it will register with the siding or main rail sections. A bar or plate 47 is mounted and secured upon the ends of certain of the ties and pivotally mounted upon this bar or plate, as at 48, are bell crank levers 49 and 50 to which the ends of the bars or rods 20 are operatively connected. An actuating rod 51 (which is operatively connected at 52 to a switch throwing mechanism not shown) is connected at 53 to the bell crank levers to cause them to move in unison. The switch operating mechanism (not shown) is, in turn, connected by a rod 54 with the usual switch points 55.

The frog rail operates simultaneously with the movement of the switch points. When the switch points are moved to permit the wheels of the rolling stock to travel on the main rails, the frog rail 11 is in alining register with the main rail sections. When the switch points 55 are moved in engagement with the siding rails, to switch the rolling stock on the siding, the frog rail may move simultaneously therewith to assume an alining register with the siding rail sections, as in Figure 3.

It will be noted that the arcuate slots 30 are of sufficient width or properly proportioned to permit of lateral play of the cam lugs and to allow the reciprocating bars to move without binding. It is obvious that should these cam lugs closely fit the opposite walls of the slots 30, it will be impossible to move the bars due to the binding action upon the walls of the slots.

The invention having been set forth, what is claimed is:

1. A monorail frog for actuation simultaneously with a switch point including a fulcrumed frog rail, a supporting base

therefor, siding and main rail sections with which the frog rail is adapted to register, locking means operatively pivoted upon the opposite sides of the frog rail at its opposite ends, abutments on the supporting base 70 with which certain of the diagonally opposite locking means engage for holding the frog rail in alining register with either the siding rail sections or the main rail sections, and means for raising the locking 75 means out of engagement with the abutments whereby the frog rail may be moved.

2. A monorail frog for actuation simultaneously with a switch point including a fulcrumed frog rail, a supporting base 80 therefor, siding and main rail sections with which the frog rail is adapted to register, locking means operatively pivoted upon the opposite sides of the frog rail at its opposite ends, abutments on the supporting base 85 with which certain of the diagonally opposite locking means engage for holding the frog rail in alining register with either the siding rail sections or the main rail sections, and means for tilting the locking 90 means out of engagement with the abutments and including means for moving the frog rail.

3. In a monorail frog for actuation simultaneously with a switch point including a frog rail disposed at the intersection of the siding and main track rails for fulcruming movement in a horizontal plane into alining relation alternately with said rails, locks pivotally and operatively supported on opposite sides of each end of the frog rail, a supporting base for the frog rail, abutments with certain of which certain diagonally opposite locks engage for locking the frog rail against movement in 105 one direction, means for holding the frog rail against movement in the opposite direction, and means for tilting the locks upwardly to free them from engagement with the abutments whereby the frog rail may 110 be moved.

4. In a monorail frog for actuation simultaneously with a switch point including a frog rail disposed at the intersection of the siding and main track rails for fulcruming movement in a horizontal plane into alining relation alternately with said rails, locks pivotally and operatively supported on opposite sides of each end of the frog rail, a supporting base for the frog rail, abutments with certain of which certain diagonally opposite locks engage for locking the frog rail against movement in one direction, means for holding the frog rail against movement in the opposite direction, and reciprocating means operatively connecting with the frog rail but adapted to move a short distance before imparting movement to the frog rail and provided with means for tilting said diago- 125 130

nally opposite locks out of engagement with their abutments to permit the frog rail to be moved.

5. In a monorail frog for actuation simultaneously with a switch point including a frog rail disposed at the intersection of the siding and the main track rails for fulcrumming movement in a horizontal plane into alining relation alternately with said rails, a cradle for the support of the frog rail, gravity actuated locking devices pivotally and operatively supported upon opposite sides of the frog rail at its opposite ends, abutments on the cradle with certain of which certain diagonally opposite locking devices engage for locking the frog rail against movement in one direction, means for preventing movement of the frog rail in the opposite direction, said pivotally and operatively supporting means for the locking devices including chairs carried by the frog rail, and reciprocating members operatively connected to the chairs for moving the frog rail upon its fulcrum and provided with means to cam against the locking devices to tilt them out of engagement with their abutments prior to imparting movement to the frog rail.

6. In a monorail frog for actuation simultaneously with a switch point including a frog rail disposed at the intersection of the

siding and the main track rails for fulcrumming movement in a horizontal plane into alining relation alternately with said rails, a cradle for the support of the frog rail, gravity actuated locking devices pivotally and operatively supported upon opposite sides of the frog rail at its opposite ends, abutments on the cradle with certain of which certain diagonally opposite locking devices engage for locking the frog rail against movement in one direction, means for preventing movement of the frog rail in the opposite direction, said pivotally and operatively supporting means for the locking devices including chairs carried by the frog rail, and reciprocating members provided with slot and roller connections with the chairs, thereby permitting the members to move slightly for imparting movement to the frog rail, said reciprocating members having cams adapted to cam against and tilt certain diagonally opposite locking devices out of engagement with the abutments prior to permitting the frog rail to move, the ends of said slots cooperating with the rollers subsequently to tilting the locking devices and thereby constituting means for moving the frog rail.

In testimony whereof he affixes his signature.

WILLIAM SCHWIER
